J. Edward Shebaud

UNITED STATES PATENT OFFICE.

HENRY P. JONES, OF BUFFALO, NEW YORK.

DRAWING-PAD DEVICE.

1,376,098.

Specification of Letters Patent. Patented Apr. 26, 1921.

Application filed August 25, 1920. Serial No. 405,854.

To all whom it may concern:

Be it known that I, HENRY P. JONES, a citizen of the United States, residing at Buffalo, in the county of Erie and State of New York, have invented certain new and useful Improvements in Drawing-Pad Devices; and I do hereby declare the following to be a full, clear, and exact description of the same, such as will enable others skilled in the art to which it appertains to make and use the same, reference being had to the accompanying drawings, and to figures of reference marked thereon, which form part of this specification.

15 Like figures of reference refer to like parts.

This invention relates to drawing pad devices.

One of the objects of this invention is to provide for the use of a mechanical, architectural or other sketcher, a manifold pad of tracing or opaque paper for preliminary work, having printed on the margin of each sheet a graduated scale, which will enable 20 the sketcher to proportion his figures without the use of a rule, thus saving time.

Another object is to provide a drawing pad which is adapted to the use of a T-square and triangle, having detachable printed 30 strips at the margin of the sheet, which the sketcher removes before filing the same away, leaving the body of the sheet of a standard size.

With these and other objects, one embodiment of this invention is illustrated in the drawings, the construction is described, its use explained and what I claim is set forth.

In the drawings,

Figure 1 is a perspective view of a drawing pad device embodying my invention.

Fig. 2 is a plan of a detached sheet showing a sketch thereon, ready for filing, having the graduated marginal strips removed.

In the figures, 1 is a thin drawing board, 45 which may be made of any suitable wall board or wood or such material as will receive tacks. Under the four corners of the drawing board 1, I preferably provide rubber pads 2, which serve, by their friction, 50 to keep the board 1 from shifting on a table, while being used. Upon the board 1, is tacked the backing 3 of the pad 4; the sheets 5 of which pad are glued together at the top 6. Each sheet 5 has narrow marginal strips 5^a 55 and 5^b at adjoining edges, which are separable from the body of the sheet 5 at the

perforated lines 7 and are divided preferably into inches, halves, quarters, and eighths, while I also provide an intermediate subdivision of one-sixth inch each, indicated by the rows of dots D, the spacing of which is the same as typewritten matter.

In using this pad device, the T-square 8 and triangle 9 serve in the ordinary way as guides in drawing, while the graduations 65 aid in dimensioning off the lines of the figure which is drawn upon the body of the sheet 5. After the drawing or sketch is complete, the marginal strips 5^a and 5^b are removed from the body of the sheet 5, leaving the sheet of some regular size, such as 8¹/₂ x 11, convenient for filing away, as is shown in Fig. 2, the edges 7^a being those from which the marginal strips 5^a and 5^b are torn.

Such a pad is also serviceable for tabulating and such vertical lines as 10, 11 and 12, may be spaced in accordance with the subdivisions of the strip 5^a, while horizontal lines as 13, may be drawn preferably spaced 80 one-sixth of an inch apart, using the dots D for guiding the spacing of such lines, as may be required for writing on the pad. 14 is a sample design sketched upon the sheet 5.

With the detachable strips 5^a and 5^b subdivided into convenient divisions printed thereon for guides, and the pad being of such construction in connection with the drawing board of the size, as to lend itself for the ready use of a suitable T-square and 90 triangle, the sketcher has at his convenience always, a fresh sheet of paper ready for a new sketch without the necessity of each time tacking a separate sheet to the drawing board before he begins, at the same 95 time, dispensing with thumb tacks.

After one drawing pad is used up, it can be removed and a fresh drawing pad tacked upon the board 1, or while the drawing pad is thick enough to give support to the T- 100 square, it can be used without mounting it upon the board 1.

Details of the embodiment of my invention herein shown and described, may be changed without departing from the spirit 105 and scope thereof, I therefore do not wish to be confined to this one embodiment, hence I claim,

1. A drawing pad comprising a plurality of sheets cut to rectangular shape and glued 110 together at one edge thereof and a marginal strip to each sheet divided from the same

- by a weakened line whereby said strip may be easily torn from the body of the sheet, and a series of equally spaced divisions marked lengthwise on said strip.
- 5 2. A drawing pad comprising a plurality of similarly sized and shaped sheets, cut to a rectangle, and glued together at one end of the sheets, and two adjoining marginal strips on each sheet, subdivided by equally spaced marks, the length of the strip, each strip being separable from the body of the sheet on a weakened line.
- 10 3. In a drawing device the combination of
- a drawing pad comprising a plurality of similarly sized and shaped sheets of paper 15 or the like, cut to a rectangle, and glued together at one end of the sheets, and two adjoining marginal strips on each sheet, subdivided by equally spaced marks, the length of the strip, each strip being separable from 20 the body of the sheet on a serrated line, and a board of the same size and shape as said sheet, to which said pad is releasably fixed.

HENRY P. JONES.
